CLAIM

The ornamental design for a beverageware lid with elastomeric ring, as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a front perspective view of the beverageware lid with elastomeric ring showing my new design;

FIG. 2 is a front perspective view thereof, the elastomeric ring being removed therefrom;

FIG. 3 is a front view thereof;

FIG. 4 is a right side view thereof, the left side being mirror symmetrical;

FIG. 5 is a rear view thereof;

FIG. 6 is a top view thereof;

FIG. 7 is a bottom view thereof;

FIG. 8 is a right side cut-away view thereof;

FIG. 9 is a front perspective view of a second embodiment of the beverageware lid with elastomeric ring;

FIG. 10 is a front perspective view thereof, the elastomeric ring being removed therefrom;

FIG. 11 is a front view thereof;

FIG. 12 is a right side view thereof, the left side being mirror symmetrical;

FIG. 13 is a rear view thereof;

FIG. 14 is a top view thereof;

FIG. 15 is a bottom view thereof; and,

FIG. 16 is a right side cut-away view thereof.

The dash-dash broken lines and unshaded surfaces bounded by broken lines form no part of the claimed design. The dash-dot line represents a cut-away portion that forms no part of the claimed design. The cross-hatch is used to indicate a difference in material between the beverageware lid and elastomeric ring.
